UNITED STATES PATENT OFFICE.

CHARLES B. ROYAL, OF CHICAGO, ILLINOIS.

LUBRICATOR FOR RAILWAY JOURNAL BOXES.

Application filed October 9, 1925. Serial No. 61,432.

This invention relates to lubricating devices and is particularly adapted to be used in railway journal boxes.

The primary object of the invention is to provide a reservoir for oil which can readily be inserted into a standard railway box or removed therefrom and which contains means for conveying oil within the reservoir to the journal as well as means for closing the top of the reservoir so as to prevent dirt and water from getting therein and to retain the oil therein except when it bears against the journal.

These and other objects, as will herein-after appear, are accomplished by this invention which is fully described in the following specification and shown in the accompanying drawings, in which:

Figure 1 is a vertical longitudinal section through a railway journal box enclosing the lubricating device;

Fig. 2 is a transverse vertical section on the line 2 of Fig. 1;

Fig. 3 is a top plan view of the lubricator removed; and

Fig. 4 is a similar view with the felt covering and supporting shoe removed.

The embodiment illustrated shows a standard railway journal 10 enclosed in a standard railway journal box 11 having an opening 12 at the front which is closed by a well known form of spring pressed cover 13 which is hingedly mounted on a pin 14. The lubricating device consists of a pan or reservoir 15 which is preferably made of sheet metal and which is preferably semi-cylindrical as shown in Fig. 2. This is so formed that when the cover 13 is raised it may be readily inserted into the journal box or withdrawn therefrom.

A shoe 16 of sheet metal or the like having the general contour of the journal 10 as shown in Fig. 2, is normally pressed upwardly toward the journal by means of coil springs or the like 17. Overlying the shoe 16 is a pad 18 of felt or the like which extends over substantially the entire top of the reservoir 15 and is secured around the edges thereof by means of a band 19 which is riveted or otherwise securely fastened thereto so that dust and water are prevented from falling into the reservoir 15.

Strips of wicking 20 or the like are secured to the upper surface of the shoe 16 and in contact with the felt 18. These extend into the bottom of the reservoir 15 so that when

the oil in the reservoir becomes low they will feed it to the felt pad 18 thereby maintaining the supply of lubricant to the journal.

The outer end of the reservoir is raised at 60 21 above the level of the bottom of the journal. Thus, since the felt 18 covers the reservoir, the oil level in the portion 21 may be maintained above the level of the bottom of the journal thereby applying a static 65 pressure thereto. A lid 22 is hingedly attached to the portion 21 and serves to cover a filling opening 23 therein.

For convenience in inserting the lubricator into a journal box a flexible wire cord or the 70 like 24 is attached by means of an eyelet 25 to the bottom of the shoe 16, the cord passing through a tube 26 which is secured to the bottom of the reservoir 15 and leads out to the upper forward corner. A button 27 is 75 secured on the outer end of the cord 24.

Thus, to remove the lubricator, the operator grasps the outer portion 21, at the same time pulling up on the button 27. This draws the shoe 16 down compressing the 80 springs 17 so that the lubricator can then be readily withdrawn from the journal box.

The pad 18 feeds oil at the point where it makes contact with the journal while at the sides and ends where no contact occurs it 85 retains the oil and at the same time keeps out dust and water, thereby keeping the oil supply pure and clean.

Buttons 28 of hard rubber, fibre, or the like, are placed at intervals about the reservoir 90 to prevent undue chafing in the journal box.

While I have shown and described but a single embodiment of this invention, it is to be understood that it is capable of many 95 modifications. Changes therefore in the construction and arrangement may be made which do not depart from the spirit and scope of the invention as disclosed in the appended claims.

I claim:

1. In a lubricator for railway journal boxes, an oil reservoir adapted to pass into and out of a journal box, an imperforate oil transmitting pad adapted to contact the 105 under side of a journal and flexibly connected to said reservoir so as to seal the top of the same, and means within said lubricator for yieldingly holding said pad in contact with said journal when in the journal box.
2. In a lubricator for railway journal

100

105

110

- boxes, an oil reservoir adapted to pass into and out of a journal box, an imperforate oil transmitting pad adapted to contact the under side of a journal and flexibly connected to said reservoir so as to seal the top of the same, means within said lubricator for yieldingly holding said pad in contact with said journal when in the journal box, and an extension on said reservoir adapted to maintain oil above the level of said pad. 5
3. In a lubricator for railway journal boxes, an oil reservoir adapted to pass into and out of a journal box, an oil transmitting pad adapted to contact the under side of a journal and flexibly connected to said reservoir so as to close the top of the same, wicks operably connected to said pad for feeding oil from the bottom of said reservoir, and means within said lubricator for yieldingly holding said pad in contact with said journal when in the journal box. 15
4. In a lubricator for railway journal boxes, an oil reservoir adapted to pass into and out of a journal box, an oil transmitting pad adapted to contact the under side of a journal and flexibly connected to said reservoir so as to close the top of the same, means for yieldingly holding said pad in contact with said journal when in the journal box, and means operable from the front of said journal box for depressing said yielding means during insertion or withdrawal of said reservoir. 25
5. In a lubricator for railway journal boxes, an oil reservoir adapted to pass into and out of a journal box, an oil transmitting pad adapted to contact the under side of a journal and flexibly connected to said reservoir so as to close the top of the same, means within said lubricator for yieldingly holding said pad in contact with said journal when in the journal box, and a flexible member operable from the front of said journal box for depressing said yielding means during insertion or withdrawal of said reservoir. 30
- voir so as to close the top of the same, means for yieldingly holding said pad in contact with said journal when in the journal box, and a flexible member operable from the front of said journal box for depressing said yielding means during insertion or withdrawal of said reservoir. 40
6. In a lubricator for railway journal boxes, an oil reservoir adapted to pass into and out of a journal box, an oil transmitting pad adapted to contact the under side of a journal and flexibly connected to said reservoir so as to close the top of the same, a frame having substantially the curvature of said journal lying beneath said pad, and means within said lubricator for yieldingly holding said pad in contact with said journal when in the journal box. 45
7. In a device of the character set forth, a stationary oil reservoir adapted to pass into and out of a journal box and adapted to be supported by a journal box, an oil transmitting pad adapted to contact the under side of a journal and flexibly connected to said reservoir so as to close the top of the same, and means within the reservoir for yieldingly holding said pad in contact with said journal when in the journal box. 50
8. In a device of the character set forth, a removable oil reservoir adapted to be supported in contact with a journal box, an oil transmitting pad adapted to contact the underside of a journal and flexibly connected to said reservoir so as to seal the top of the same, and means for yieldingly holding said pad in contact with said journal when in the journal box. 55

CHARLES B. ROYAL.
